WORK HOLDER

John Jesionowski, Schenectady, N. Y.

Application June 9, 1945, Serial No. 598,604

8 Claims. (Cl. 90—60)

1

This invention relates to work holders, and more particularly to a vise having a bed plate on which are mounted a fixed jaw and a rectilinearly movable adjustable jaw. The invention is shown as applied to a sine vise and it has certain special advantages in that connection, but it may be applied to work holders used on machine tools and the like.

One of the objects of the invention is to provide a vise in which the work piece held in place between the jaws may be positioned at will in an accurate manner in any of a number of angles relatively to the longitudinal axis of the vise in order to facilitate operations of tools upon the clamped work piece.

Another object is to provide a simple device adapted to be associated with one of the jaws whereby the work piece clamped against a face of this jaw can be positioned in an accurate manner in various positions in a plane parallel to the clamping face of the jaw.

Another object is to provide a simple appliance whereby the work piece can be adjusted about an axis disposed within and transversely of the jaw to which the appliance is applied.

To these and other ends, the invention consists in the novel features and combinations of parts to be hereinafter described and finally pointed out in the claims.

In the accompanying drawings:

Fig. 1 is a top plan view of a sine vise embodying my invention, showing the movable jaw spaced at some distance from the fixed jaw;

Fig. 2 is a side elevation, partly in section, showing the vise with a work piece held in position between the jaws;

Fig. 3 is an end view of the device shown in Fig. 2, looking from the right hand end;

Fig. 4 is a section on line 4—4 of Fig. 2;

Fig. 5 is an end view of a vise of somewhat modified form;

Fig. 6 is an end view of a vise of still further modified form;

Fig. 7 is a horizontal sectional view of a vise such as shown in Fig. 6, illustrating the use of a micrometer gauge in measuring the angle.

Fig. 8 is a top plan view of another form of work holder embodying the invention;

Fig. 9 is a right hand end view of the holder shown in Fig. 8, showing a work piece in place of the holder; and

Fig. 10 is a section on line 10—10 of Fig. 8.

For purposes of illustration I have shown my improvements applied to a sine vise having a fixed jaw and a rectilinearly movable adjustable

jaw, and the device or appliance for controlling the location of the work piece is associated with the fixed jaw. This illustration, however, is only by way of example. A sine vise, such as illustrated, is of a structure such that the bed plate can readily be held in various positions in which its longitudinal axis is tilted relatively to a horizontal plane. This enables the work piece to be correspondingly tilted for facilitating operations 5 to be performed thereon, but I have discovered that the adjustability of the work piece should be of greater scope, and that operations upon the work piece, in the way of cutting, filing, or the like, are greatly facilitated if there is adjustment 10 of the work piece in a controlled manner in a plane perpendicular to the longitudinal axis of the vise.

In the drawing, the sine vise is shown as having a bed plate 10 having a fixed jaw 11 at one 20 end secured to the upper face of the plate and a rectilinearly movable jaw 12 mounted on the plate to move longitudinally thereof. The jaw 12 is adjusted by an adjusting device 13, a part of which turns in an upstanding lug 14 on the bed plate, the adjustment being effected by turning a suitable operating head 15. Associated with the bed plate, at the under part thereof, are fixed rolls 16 and 17 which extend transversely of the bed plate and enable the same to be readily held 25 in tilted position when the vise is tilted lengthwise in the manner above mentioned, that is to say, by moving the longitudinal axis of the vise to a desired angle relatively to a horizontal plane.

It will be seen that the fixed jaw 11, at the right 30 hand extremity of the vise (Figs. 1 and 2), is cut away at 18 to provide a recess in the face of the jaw having a partly circular inner surface 19. The circle is not complete, for the recess 18 extends completely to the straight upper surface 20 of the jaw, providing the partly round recess 18 with an open upper end portion 21.

The inner surface 19 of recess 18 is formed on an arc whose center coincides with the center of a longitudinal round bore 22 extending through 45 the jaw 11, the right hand end of the bore (Fig. 2) opening into recess 18.

It will be noted that to the left or forwardly of the jaw 11 (Fig. 2), adjacent the lower part of the jaw, is located a supporting plate 23 which 50 assists in locating the work piece 24 in the manner hereinafter pointed out. This plate 23 is in the shape of part of a disk, in this particular case being of half-moon formation, and it is located with its straight edge 25 uppermost. At the 55 lower part, this plate is received in a socket 26a

between the lower part of the jaw 11 and a shoulder 26 projecting upwardly from the bed plate, the arrangement being such that the lower part of the plate 23 is confined while its upper part projects somewhat into the space 27 provided between what may be termed the front face of the jaw 11 and the rear face of the jaw 12, whereby the edge portion 25 of plate 23 is adapted to form a bottom support for the work piece 24. At its upper part, the plate 23 is made integral with or secured to a cylindrical shank 28 fitting within the bore 22 and having its forward end flush with the forward face of jaw 11. At its rear end, the shank 28 is provided with a kerf 29 in which is pinned, by a pin 30, the rounded end 31 of a lever 32. This lever is adapted to be adjusted manually from the right hand or rear end of the vise, for the purpose of adjusting the plate 23 about the longitudinal axis of the bore 22 and shank 28 in order that the work piece may be supported at different angles in a plane transverse to the vise.

Fig. 2 shows the vise with a work piece 24 between the jaws, the half-moon plate 23 being shifted to one of its permissible angular locations. It will be observed that, with the parts in the position shown, the adjusting lever 32 is received within the recess 18. In the form shown, the lever 32 has a small cylindrical handle 33 at the free end substantially in contact with the curved surface 19 of the recess. In this position, the main part of the lever 32 is parallel to the rear face of jaw 11 and in contact with that face.

On the handle member 33 is a line 34 adapted to register with a scale 35 applied in a suitable manner to the rear face of the fixed jaw. This scale comprises indicia of various angles, as shown more particularly in Fig. 3, in order that the lever 32, and thereby the plate 23, may be turned to a position in which the work will be held at the desired angle.

It will be evident from Fig. 2 that, when jaw 12 is forced against the work piece, the work piece will hold the plate 23, and its associated members 28 and 32, in the positions to which they have been adjusted. The parts 23, 28, and 32 fit in their socketed receiving means in such a manner that there is no play. If it is desired to change the angle of the plate 23, the adjusting means 13 is loosened so as to draw away the jaw 12 from the work piece and the lever 32 can then be turned to bring the plate 23 to the angular position desired.

It is to be noted that the parts 23, 28, and 32 are readily removable from their socketed receiving means when this is desired. In Fig. 2, the lever 32 is disposed at approximately right angles to its carrying part 28 but it can be swung on its pivot 30 to a position in which it is aligned with part 28, and then, by turning part 23 into an upper position with respect to its turning axis, the assembly 23, 28, 32 can be displaced to the left with reference to Fig. 2 in order to remove it from its associated jaw. It will also be understood with what readiness this assembly can be restored to its operating position.

In the modification shown in Fig. 5, the shank portion 28 carries a lever 32' having a pointed end 36 which moves over an angle scale 37.

Taking the work piece 24 as an example, it is evident that for cutting, filing, or like operations upon this piece it is of advantage to be able to tilt the vise lengthwise with reference to a horizontal plane, as is done in sine vises. In the present case, however, it is possible to adjust the

work piece at compound angles, for it is possible to adjust it in a plane perpendicular to the longitudinal axis of the vise as well as in a vertical plane longitudinal to the vise. This greatly enlarges the scope of the device because it is possible to locate the work piece relatively to any desired plane—in other words, universally—by proper adjustment of the bed plate relatively to a machine or support and by proper adjustment of the plate 23 relatively to the bed plate. As a result, the machining or other operations upon the work are very much facilitated and it is possible to increase production materially.

In the form of vise shown in Fig. 6, the construction in general is similar to that illustrated in Figs. 1 to 5 inclusive, but the lever 32'' has an operating handle 38 flattened off at the outer side, as indicated at 39, and adapted to move within a rectangular recess 40 provided upon the rear face of the vise. In order to locate the work in a very accurate manner, measuring blocks such as indicated at 41 may be introduced into the recess 40 between the handle 38 and one of the side walls of the recess, as shown.

Fig. 7 shows a vise of the same kind shown in Fig. 6, illustrating the use of a micrometer gauge 42 for measuring the angle of the work. Here the micrometer gauge has a fixed projection 43 abutting one side of the handle 38 whereas the spindle 44 of the gauge abuts at its inner end against a planar surface 45 provided externally on a side wall defining the recess 40.

Another difference between the form of Fig. 7 and that of Figs. 1 to 4 inclusive arises from the fact that in the case of Fig. 7, the shank or plug 28' may be held against turning by clamping means engaging the same at the respective sides. At each side of the plug or shank, a transverse bore is provided in the supporting block, said bore having a screw member 65 operating therein and adapted to be turned from the exterior of the vise. The screw member 65 is adapted to push a soft metal piece 66 against the side of the block 28' in order to hold it firmly in place.

In Figs. 8, 9, and 10, there is shown a work holder having a base 46 which is a sine base having rolls 47 and 48 associated with the respective extremities. From the base rises a projection or jaw 49 having a horizontal longitudinal bore 50 similar to the bore 22 previously mentioned. In the bore 50 is a work holding and positioning device similar to that previously described, including a plug-like member 51 with a work holding shelf 52 and also including a pivoted operating lever 53. In this form, however, the work holding shelf 52 is on a semi-circular part 54 that is adapted to be engaged and clamped by a clamping rod 55 located in a longitudinal bore 56 in the base. The rod 55 is held in position by a screw plug 57 having a polygonal socket 58 (Fig. 9) by which it may be turned from the end of the base.

In this form of the work holder, the work can be clamped on the projecting member 49 in a suitable manner. A number of screw sockets 59 are provided in this member on the inner face thereof at various points above the work holding shelf and, if desired, at points adjacent the respective ends of the shelf. Fig. 9 shows by example the manner of clamping the work piece. Here a work piece 60 is held on the shelf 52, with the shelf in a slightly inclined position, by means of two clamping clips 61 and 62 held in place by screws 63 and 64 screwed into two of the

screw sockets 59. The work holding shelf is, of course, firmly held in position by the clamping rod 55 engaged therewith, which clamping rod is in turn engaged by the clamping screw 57.

It will be seen from the above that the invention provides a very simple and effective work holder in which the work can be readily given an accurate compound adjustment. The work piece can be very readily and accurately adjusted in planes that are perpendicular to each other.

Various changes in the organization of parts and details can be made without departing from the principles of the invention or the scope of the claims.

What I claim is:

1. A sine vise having a base plate with transverse roll members adjacent the respective ends at the underneath portion thereof whereby the plate may be positioned at various angles to a horizontal plane, a fixed jaw and a movable jaw associated with said plate at the upper portion thereof and having opposing portions adapted to clamp a work piece, and means including a rockable angularly adjustable plate supporting the work piece from beneath in the space between the jaws for setting the work piece between the jaws at any of a number of predetermined angles in a vertical plane extending transversely of the jaws.

2. A sine vise having a base plate with transverse roll members adjacent the respective ends at the underneath portion thereof whereby the plate may be positioned at various angles to a horizontal plane, a fixed jaw and a movable jaw associated with said plate at the upper portion thereof and having opposing portions adapted to clamp a work piece, and means including a rockable angularly adjustable plate supporting the work piece from beneath in the space between the jaws for setting the work piece between the jaws at any of a number of predetermined angles in a vertical plane extending transversely of the jaws, said means also including an adjusting shank connected to said last named plate and extending axially of one of said jaws in a socket provided in said jaw.

3. A sine vise having a base plate with transverse roll members adjacent the respective ends at the underneath portion thereof whereby the plate may be positioned at various angles to a horizontal plane, a fixed jaw associated with said plate at the upper portion thereof and adapted to clamp a work piece, and means including a rockable plate having a body seated in the base plate supporting the work piece from beneath in the space adjacent a clamping face of the jaw for setting the work piece in any of a number of predetermined angles in a vertical plane extending transversely of the vise, said means also including an adjusting shank connected to said last named plate and extending axially of said jaw in a socket provided in said jaw, said adjusting shank having an operating lever swingable over a face of said jaw.

4. A work holder having a base plate and jaws mounted on said base plate adapted to clamp a work piece therebetween with a space between the base plate and the lower part of the work

piece, a supporting element engaged with the lower part of the work piece from beneath to support it between the jaws in any of a variety of angles in a vertical plane transverse to the jaws, and an adjusting device for said supporting element extending through one of the jaws.

5. A work holder having a base plate and jaws mounted on said base plate adapted to clamp a work piece therebetween with a space between the base plate and the lower part of the work piece, a supporting element engaged with the lower part of the work piece from beneath to support it between the jaws in any of a variety of angles in a vertical plane transverse to the jaws, and an adjusting device for said supporting element extending through one of the jaws and having at the face of said jaw remote from the work piece an operating lever sweeping over a recessed portion on the jaw.

20 6. A work holder comprising a sine base having sine rolls adjacent the respective ends, a member projecting upwardly from the base, said member having a bore extending therethrough longitudinally of the base, a shank rotatably mounted in said bore, a work supporting plate connected to said shank on one side of said projecting member and provided with a work supporting shelf, a lever connected to the shank adjacent its other end for turning the shank on its axis, and means for 25 clamping the shelf in adjusted position, said projecting member being provided on a face adjacent said shelf with a plurality of sockets for clamping screws.

7. A work holder comprising a sine base having 30 sine rolls adjacent the respective ends, a work-clamping jaw member projecting upwardly from the base, said member having a bore extending therethrough longitudinally of the base, a shank mounted in said bore and adapted to be turned about its axis, a work-supporting plate located at one side of said clamping member and rigid with said shank so as to be turned thereby and provided with a work-supporting shelf, and a lever located at the other side of said clamping member and connected to said shank and adapted to be manipulated for turning the shank on its axis and thereby adjusting the work-supporting shelf.

8. A work holder such as set forth in claim 7, in which the lever is located in a recess at the 40 face of the work-clamping member and has a free end adapted to move over an indicating scale on the work-clamping member.
